signor to A. F. Dormeyer Mfg. Co., Chicago,
Ill., a corporation of Illinois

Application September 2, 1938, Serial No. 79,683

Term of patent 3½ years

To all whom it may concern:

Be it known that I, Hermann M. Alfred Strauss, a citizen of the German Republic, residing at Chicago, in the county of Cook and State of Illinois, have invented a new, original, and ornamental Design for Supporting Stands for Motor Driven Food Appliances or Similar Articles, of which the following is a specification, reference being had to the accompanying drawing, forming part thereof.

Fig. 1 is a view in perspective of a supporting stand for motor driven food appliances or similar articles, embodying my new design;

Fig. 2 is a slightly enlarged front elevational view thereof;

Fig. 3 is a slightly enlarged top plan view thereof;

Fig. 4 is a slightly enlarged side elevational view thereof;

Fig. 5 is a slightly reduced rear elevational view thereof.

I claim:

The ornamental design for a supporting stand for motor driven food appliances or similar articles, as shown.

HERMANN M. ALFRED STRAUSS.
